UNITED STATES PATENT OFFICE.

EMIL E. FULLER, OF WOONSOCKET, RHODE ISLAND, ASSIGNOR TO SHAMBOW SHUTTLE COMPANY, OF WOONSOCKET, RHODE ISLAND, A CORPORATION OF RHODE ISLAND.

SHUTTLE.

Application filed December 2, 1927. Serial No. 237,179.

The present invention relates to an improvement in shuttles.

In silk shuttles a pivoted tension lever having a plurality of thread eyes on one arm, has long been used in connection with a series of pins to apply tension to the yarn being discharged by the shuttle. The other arm of the tension lever has been attached to one end of a piece of rubber elastic, the other end of the elastic being secured to a pin in the shuttle, the pull of the rubber elastic tending to move the tension lever in the direction to cause it to take up the yarn when the pull on it is reduced in the operation of the shuttle. This rubber elastic has long been a source of serious criticism on the part of the weavers and of the shuttle manufacturers, but its use still obtains, and no satisfactory substitute has gone into extended use.

The object of the present invention is to produce an improved form of tension for shuttles, and the invention consists in the shuttle tension hereinafter described and particularly defined in the claims.

In the accompanying drawings illustrating the preferred form of the invention, Fig. 1 is a plan of the eye end of a silk shuttle embodying the present invention; Fig. 2 is a rear elevation of this portion of the shuttle; Fig. 3 is a horizontal section showing the shuttle tension and its controlling means; Fig. 4 is a front elevation of this end of the shuttle; and Fig. 5 illustrates a modification.

The illustrated embodiment of the invention is described as follows: The shuttle body 10 carries the usual bobbin 11 in the bobbin recess 12. From the bobbin the yarn 13 extends through the eye 14 to the pin 15, and thence through the eye 16 of the tension lever 17, from which it passes over the successive pins 18 and through the remaining eyes 19 of the tension lever. The tension lever 17 is pivoted on the screw 20, and provided with a short spring-pressed arm 21, which embraces the spring-carrying rod 22. This spring-carrying rod is supported in the posts 23 and 24. The pin 24 is provided with a plain hole to receive the spring rod 22. The pin 23 is similarly provided with a plain hole, but it is also provided with a longitudinal hole which receives a screw 25 by means of which the position of the spring rod 22 may be fixed. Secured on the spring rod 22 is the spring button 26 for the spring 27, which

encircles the spring rod 22. The other end of the spring 27 presses against the spring arm 21 of the tension lever, a washer 28 being interposed to secure good operating conditions. The pressure exerted by the spring 27 on the spring arm 21 of the tension lever tends to turn the tension lever into the position shown in Fig. 3, thereby forming a series of bights in the yarn 13 being discharged from the shuttle. When a greater tension is applied to the yarn, the tension lever will be turned, drawing the eye arm up toward the row of pins 15, 18, and thereby moving the spring arm 21 of the lever in the direction to compress the spring 27. With some threads it is necessary to apply a greater spring pressure to the tension arm than with others, and this is readily accomplished by loosening the screw 25 and moving the spring rod 22 in one direction or the other—to the right, as viewed in Fig. 3, to reduce the tension on the thread, and to the left to increase it. After the spring rod has been moved to the desired position, the set screw 25 is screwed down and the spring is held in its adjusted position.

It is to be observed that this construction is simple in form, and is made of durable material. The eye portion of the spring arm 21 is made elongated so that the turning of the tension lever does not cause any binding of the arm on the spring rod 22. The spring 27, being a compression spring, is a durable form of spring and is preferred to a tension spring for that reason. Moreover, the use of this durable construction eliminates a great waste of time in replacing broken rubber elastics in the ordinary form of tension lever heretofore employed. The construction is simple and easily assembled.

In assembling the device the spring rod receives the spring and the washer, and the right-hand end of the spring rod, as viewed in Fig. 3, is thrust into the opening in the shuttle by inserting it above the pin 24, and thrusting out toward the tip in a generally inclined position toward the tip of the shuttle, and moving out in that direction until the spring washer is carried beyond the eye of the spring arm 21 of the lever, at which time the spring rod 22 is moved upwardly, as viewed in Fig. 3, until it is laid into the open end of the loop formed in the lower end of the spring arm. Then the spring rod is moved in the opposite direction, and its end

is inserted in the hole in the post 23. It is carried in this direction into the recess 30, whereupon the rod is moved until the right-hand end is caused to enter the hole in the pin 24. The pressure of the spring against the spring arm of the tension lever will now move the rod to the right, as viewed in Fig. 3, and the parts will be assembled in place ready for adjustment to secure the desired 10 tension to be applied to the tension lever.

Fig. 5 illustrates a modification wherein the posts 31 and 32 replace the posts 23 and 24, and the rod 33 is used in place of the rod 22. This spring rod 33 is received in 15 holes in the posts 31 and 32 as in the other form, but its adjustment longitudinally is secured by screw-threading either one end or the other and providing it with set nuts 34 and 35. Where nicety of adjustment is 20 desired this modification may be used. In general, however, the cheapness of the other construction and the celerity with which adjustment of the spring tension may be made render its use preferable. Other constructions may be employed within the scope of 25 the claims.

Having thus described the invention, what is claimed is:

1. A shuttle provided with a tension lever 30 pivoted in a recess therein, said tension lever having an eye arm and a spring arm, a spring rod supported in the shuttle and

provided with a button, a compression spring on the spring rod engaging the spring arm at one end and the button at the other end, 35 and means for securing the spring rod in position in the shuttle.

2. A shuttle having a spring lever tension device, consisting of a tension lever pivoted in the shuttle provided with an eye arm 40 and a spring arm, a spring rod provided with a button, posts supported in the shuttle provided with holes to receive the spring rod, one of said posts being provided with a set screw for securing the spring rod in 45 adjusted position in the posts, a compression spring embracing the spring rod and engaging the spring arm of the tension at one end and the button fixed on the spring rod at the other end.

3. A shuttle having a spring lever tension device comprising a tension lever pivoted in the shuttle, having an eye arm and a spring arm, the spring arm having an open-sided eye, a spring rod received in the open-sided 55 eye of the spring arm, means for supporting the spring rod having provision for adjusting it, and a compression spring on the spring rod for applying pressure to the spring arm of the tension lever.

In testimony whereof I have signed my name to this specification.

EMIL E. FULLER.
